(57) **CLAIM**

The ornamental design for a high power module for controller of transport climate control system, as shown and described.

DESCRIPTION

FIG. 1 is a top perspective view of a high power module for a controller of a transport climate control system showing our new design;

FIG. 2 is a left side perspective view thereof;

FIG. 3 is a front elevation view thereof;

FIG. 4 is a rear elevation view thereof; and

FIG. 5 is a left side elevation view thereof;

FIG. 6 is a right side elevation view thereof; and,

FIG. 7 is a top plan view thereof.

We note that the high power module for a controller of a transport climate control system shown in FIGS. 1-7 can be used, for example, in transport climate control applications. The controller can be used to control environmental condition(s) (e.g., temperature, humidity, air quality, and the like) within a climate controlled space of a transport unit (e.g., a truck, a container (such as a container on a flat car, an intermodal container, a marine container, a rail container, etc.), a box car, a semi-tractor, a bus, or other similar transport unit).

The broken lines shown in the FIGS. 1-7 are for illustrative purposes only and forms no part of the claimed design.

The features in the FIGS. 1-7 shown within the perimeter of the dash dotted line (-•-•-), particularly FIG. 7, are for illustrative purposes only and forms no part of the claimed design.

1 Claim, 5 Drawing Sheets
